(57) **CLAIM**

The ornamental design for an inflator, as shown and described.

DESCRIPTION

FIG. 1 is a front perspective view of an inflator.

FIG. 2 is a top view of the inflator shown in FIG. 1.

FIG. 3 is a front view of the inflator shown in FIG. 1.

FIG. 4 is a right side view of the inflator shown in FIG. 1.

FIG. 5 is a left side view of the inflator shown in FIG. 1.

FIG. 6 is a bottom view of the inflator shown in FIG. 1; and, FIG. 7 is a rear view of the inflator shown in FIG. 1.

The broken lines in FIG. 4 are included for the purpose of illustrating portions of the inflator that form no part of the claimed design.
